GAME BOARD

Henry E. Martens and Charlotte M. Martens, both of 35 Spring Road, Kentfield, Calif.

Filed July 23, 1963, Ser. No. 75,940

Term of patent 14 years

(Cl. D34—5)

FIG. 1

The board is of conventional thickness.

The essential features of our design reside in the portion shown in full lines.

We claim:

The ornamental design of the game board, as shown and described.
